The ornamental design for a motorcycle tire, as shown and described.

DESCRIPTION

FIG. 1 is a perspective view of a motorcycle tire showing my design;

FIG. 2 is a front view thereof;

FIG. 3 is a top view thereof;

FIG. 4 is a right side view thereof;

FIG. 5 is a fragmentary enlarged front view showing the details of the tread portion thereof; and,

FIG. 6 is a section view taken along line 6-6 in FIG. 5. The broken lines in the drawing figures show portions of the tire that are not being claimed and thus form no part of the claimed design.
